US0D1110670S

(12) United States Design Patent (10) Patent No.: US D1,110,670 S
(45) Date of Patent: * Jan. 27, 2026

(54) DELIVERY BOX

(71) Applicant: SUNCAST TECHNOLOGIES, LLC,
Palm Beach Gardens, FL (US)

(72) Inventors: Stephen Whitehead, Elgin, IL (US);
Robert Kopp, Elburn, IL (US);
Torrence Anderson, Overland Park, KS
(US); Michael Funk, Elgin, IL (US)

(73) Assignee: Suncast Technologies, LLC, Palm Beach Gardens, FL (US)

() Term: 15 Years

(21) Appl. No.: 29/964,925

(22) Filed: Sep. 25, 2024

(51) LOC (15) Cl. 99-00

(52) U.S. Cl.

USPC D99/29

(57) CLAIM

The ornamental design for a delivery box as shown and described.

DESCRIPTION

FIG. 1 is a top, front, right side perspective view of a delivery box showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions of the delivery box illustrated in broken lines form no part of the claimed design.

1 Claim, 7 Drawing Sheets
